UNITED STATES PATENT OFFICE.

LEO A. HENTER, OF HOT SPRINGS, MONTANA.

CLIP AND COMB.

Application filed October 15, 1924. Serial No. 743,800.

To all whom it may concern:

Be it known that I, LEO A. HENTER, a citizen of the United States, residing at Hot Springs, in the county of Sanders and State of Montana, have invented certain new and useful Improvements in a Clip and Comb, of which the following is a specification.

This invention relates to improvements in combs and clips therefor.

10 The primary object of the invention is the provision of a comb with an improved clip by means of which the comb may be attached to apparel of a person in a convenient manner so that the comb is entirely hidden behind the apparel.

15 A further object of this invention is the provision of a novel detachable clip for combs or the like, which is of novel formation in that the article which it is adapted to support may be hidden within a pocket, and yet attached to the flap of the pocket.

20 A further object of the invention is the provision of a novel type of detachable clip which may be used to support various objects, such as combs, pens, pencils and the like.

25 Other objects and advantages of this invention will be apparent during the course of the following detailed description.

30 In the accompanying drawing, forming a part of this specification, and wherein similar reference characters designate corresponding parts throughout the several views,

35 Figure 1 is a cross sectional view taken through a garment, showing a pocket therein, and the relation in which the improved clip may support a comb in the pocket in attached relation to a flap of the pocket.

40 Figure 2 is an enlarged view, partly in section, showing novel details of the clip in its attached relation on a comb.

Figure 3 is a rear elevation of the clip attached to a comb.

45 Figure 4 is a fragmentary view of an end of the comb, showing the construction thereof for cooperation receiving the clip.

In the drawing, wherein for the purpose of illustration is shown the preferred embodiment of this invention, and which has been generically claimed in my co-pending application, Serial Number 699,907, filed March 17, 1924, the letter A may generally designate a comb, which may include novel features adapted to receive the detachable

clip B, so that the comb may be supported in the pocket of a garment F.

The comb A may be of any approved construction, and includes the back 10, outwardly of which the spaced teeth 11 extend. 60 Adjacent an end edge 12 of the comb A, and inwardly of a side surface of the back 10, a pair of recesses 13 and 14 are provided, which are arranged in alignment longitudinally of the back 10. 65

The clip B is of a novel construction, and consists of a substantially U-shaped attaching portion 15, and a spring tongue 16 connected to the portion 15 by means of an arcuate bight 17. 70

The attaching portion 15 is preferably U-shaped, although the same need not necessarily be of this shape, since it may be of a different shape when adapted to support an article different in structure from a comb. 75

However, in the preferred instance the attaching portion 15 comprises the substantially parallel side legs 19 and 20 which may be of equal length, connected by an arcuate bight portion 21. The bight portion 17 80 which connects the resilient tongue 16 to the attaching portion 15 is attached, as at 23, contiguous with the leg 19 of the attaching portion 15, and so that the arcuate bight portion 17 extends upwardly in spaced relation above the bight portion 21 of the attaching portion 15. The bight portion 17 is struck from a larger radius than the bight portion 21, so that the tongue 16 extends downwardly along in spaced relation with 85 the leg 20, and slopes inwardly as at 24 adjacent its free end, and at its free end is preferably provided with a clamping ball 25.

Referring to the application of the improved clip upon the comb A, the attaching portion 15 is slipped over the end of the comb A so that the spaced lugs 30 and 31, which are formed upon the inside surface of the leg 19, engage in detachable manner 95 in the recesses 13 and 14 respectively of the comb A. The legs 19 and 20 of the attaching portion 15, of course, grip the back of the comb in a secure clamping relation, due to their inherent tendency to spring toward 100 each other, and the bight portion 21 of the clip extends upwardly above the top edge of the comb. The bight portion 17 of the clip B extends in spaced relation outwardly 105 of the end of the comb, and the tongue 16 110

extends downwardly along the side of the comb with the ball 25 in clamped engagement against the side of the comb, substantially as is illustrated in Figure 2 of the drawings.

As to the application of the comb and the clip upon the garment F, the comb is slipped into the compartment 35 of the pocket formed in the garment F, and is entirely hidden therein. The upper edge of the pocket flap 40 fits into the space between the tongue 16 and the leg 20 of the attaching portion 15, with the upper edge of the flap 40 projecting into the space immediately below the bight portion 17 and above the bight portion 21, so that the only portion visible exteriorly of the pocket is the spring tongue 16 and the bight portion 17.

From the foregoing description of this invention it is apparent that a novel type of clip has been provided, which cooperates in a novel manner with the article which it is adapted to support whereby to support the same in novel and detachable relation within the pocket of a garment or the like.

Various changes in the shape, size, and arrangement of parts may be made to the form of the invention herein shown and described, without departing from the spirit of this invention or the scope of the claims.

I claim:

1. In a device of the class described the combination of a comb provided with a pair of spaced recesses in a side thereof, a spring metal clamping portion providing a pair of lugs extending inwardly thereof adapted to be snapped into the recesses of said comb, and a resilient tongue connected to the U-shaped clamping portion.

2. As an article of manufacture a clip comprising a U-shaped attaching portion including a pair of spaced legs and connected by a bight portion, a tongue, and a bight portion connecting the tongue adjacent the bight portion of the attaching portion so that the tongue extends outwardly from one of said legs of the attaching portion with the bight portion of said tongue extending over and above the bight portion of said attaching portion.

3. As an article of manufacture a clip comprising a short attaching portion which forms a pocket therein open at one end, a long gripping tongue, and a bight portion resiliently connecting the gripping tongue with the closed end of said attaching portion so that said bight portion extends outwardly of said closed end and supports the gripping tongue in spaced resilient relation along side of the attaching portion with the free end thereof extending beyond the open end of the attaching portion for a considerable distance.

4. As an article of manufacture a clip comprising a pocketed attaching portion having an opening at one end and being closed at the opposite end, a tongue, and a bight portion resiliently connecting the tongue to the attaching portion at the closed end thereof adjacent one side of the pocketed attaching portion with the said bight portion extending upwardly over and in spaced relation with the tongue extending along side of the pocketed attaching portion at the opposite side from that side of said pocketed portion to which the bight portion is connected.

LEO A. HENTER.
